HAND PUPPET

Tomoji Ohnuki, 18-4 Suwada 2-chome,
Ichikawa, Japan

Filed July 17, 1972, Ser. No. 272,187

Term of patent 14 years

Int. Cl. D21—01

U.S. Cl. D34—4 R

Fig. 3

FIG. 1 is a front elevational view of a hand puppet embodying my new design;

FIG. 2 is a side elevational view of the hand puppet, the opposite side being identical thereto; and

FIG. 3 is a rear elevational view thereof.

I claim:

The ornamental design for a hand puppet, as shown.
